EXPANSION BELT FOR GARMENTS

Amedeo D. Grisanti, Mount Vernon, N. Y.

Application June 19, 1947, Serial No. 755,653

2 Claims. (Cl. 2—322)

1

This invention relates to new and useful improvements in belts for the support of trousers, skirts of any other appropriate type of garment for men, women or children.

The invention provides an expansion belt including a belt member for encircling the waist, as heretofore, and having overlapping ends at the front of a pair of trousers or at a placket adjacent the side of a side opening skirt; but the new belt assembly includes, in addition to the belt member, means of a novel type for holding the overlapped ends of the belt member in the desired overlapping arrangement. At the same time, the new belt assembly includes means for nevertheless rendering the belt assembly expansible, and, in the latter connection, means for permitting adjustment of the expansibility of the belt assembly.

In attaining the objects of the invention, an arrangement is provided whereby the overlapped ends of the belt member may be positioned to retain their overlapped relation regardless of variations in the effective length of the belt assembly as such length automatically varies as the wearer assumes various postures or as his waist circumference changes from any cause. These results are obtained in part through the provision of guiding means carried by a portion of the belt member remote from the tongue end of the same, and through which guiding means the tongue end of the belt proper may be threaded or passed and thereafter slidably shifted as the belt assembly varies in agreement with waist circumference changes. In these connections, one or more loops are provided on the belt member, with or without a buckle.

In one way of carrying out the invention, a single such loop is employed, preferably in combination with a non-locking type of buckle; and in another way of carrying out the invention, a plurality of loops are employed, preferably three, these loops being secured to the belt member at spaced points along its length.

A further feature of the invention is a belt assembly so arranged that when worn, the portion thereof which is to lie at the front of the wearer is downwardly curved over a distance from about one hip to the other; thereby to obtain a utility which will later be explained.

The ordinary type of belt, nothing more than a straight strip of leather, canvas or like non-stretchable material, one inch or more in width, and with one of various types of buckles at one end, has never given the wearer comfort; nor does this belt sit properly around the waist, especially

2

when used with trousers. The downward curvature just above referred to is of special value to overcome this difficulty.

The use of a non-stretchable belt member, yet the provision with the latter of an expansible belt as aforesaid, is a particularly important feature of the invention. This objective is attained by employing, in combination with a belt member substantially non-stretchable from end to end, a guiding means for the belt member carried near the end of the belt proper remote from its tongue end and through which guiding means the tongue adjacent end of the belt member is slidable in one direction or the other, and a lengthwisely resiliently stretchable strap-form belt-auxiliary inside the belt member is connected at different ends to different parts of the belt member and also slidable in one direction or the other through said guiding means.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a side elevation of one form of belt pursuant to the invention, with its ends overlapped as they would be when the belt is finally placed around the waist of the wearer.

Fig. 2 is an elevational view showing the inside of the front portion of said belt, this view being partially in section because the same was taken on line 2—2 of Fig. 1.

Fig. 3 is an exploded perspective view of the belt of Figs. 1 and 2, that is, with the parts unnaturally separated in order to facilitate ready understanding of the invention.

Fig. 4 is a detail view in top plan of parts of the belt where the same is adapted for attachment to a button sewed at the front of a pair of trousers.

Fig. 5 is a fragmentary elevational view, looking toward the inside of a modified form of belt according to the invention, looking toward the front portion of the belt where the same is equipped with features pursuant to the invention; the one part omitted being merely an intermediate length of the belt member.

Fig. 6 is an enlarged detail view in perspective showing certain of the features of Fig. 5 and their relative arrangement in a manner so as better to clarify the showing of Fig. 5.

Fig. 7 is a view similar to Fig. 3, but illustrating the embodiment of Figs. 5 and 6.

Referring to the drawing in detail, and first particularly to Figs. 1 through 4, in which connection it is explained that in Fig. 3 no attempt has been made to show the downward front curvature of the belt, as shown in Figs. 1 and 2, and this with the idea of making Fig. 3 as simple as possible, and in which connection it is further explained that Fig. 3 has been further simplified by omitting showings of the stitches seen in Figs. 1 and 2, the new belt assembly as here shown incorporates a belt member 15 of substantially non-stretchable material.

The belt member 15 is shown as having a pointed or tongue end 16. The opposite end of the belt member is marked 17.

As the invention has been satisfactorily practiced, the belt member is made of a material commonly called rayon cotton belting, $2\frac{1}{4}$ inches wide with finished edges. The belting is folded longitudinally so that the finished edges meet at the inside surface of the belt member along the center line thereof, whereupon stitchings 18 are applied, thus making a light and yet a very strong belt and one as strong as any leather belt of comparable thickness.

Along a length of the belt member 15 adjacent its end 17, and uniformly spaced apart are three loops 19, 20 and 21 secured to the belt member, at the inside thereof, by stitchings as indicated at 22. As will be noted from Fig. 1, the stitchings 22 do not extend to or through any parts of the loops facing the exterior of the belt proper. The last mentioned parts of said loops, then, are clearly slide guide means; and through such slide means, when the belt is placed on the waist, the tongue end 16 of the belt member is passed, as clearly shown when Fig. 1 is taken with Fig. 3.

In donning the new belt relative to a pair of trousers the center loop will be an indexing means for proper placement of the belt, that is, for lying opposite the front center of the trousers.

Experiments have shown that to obtain most efficiency in use of the belt, the space between each two adjoining loops should be one-sixteenth of the size of the waist.

A button hole 23 is provided in the belt proper 15, running lengthwise thereof and placed just alongside the center loop 19. This button hole coacts with a button 24 shown in Fig. 4, which should be sewed on the front of the trousers 25 at the outside of the fly 26. This arrangement provides a means for holding the belt stationary 55 and always properly centered at the front of the waist.

Fixed to the belt member 15 is a male snap fastener 27. In the case of a belt for a thirty-two inch waist, which is here shown, this fastener is desirably placed about one-quarter of an inch to the right of the loop 21 as the parts are seen in Fig. 3.

Stitched as at 28 to the inside of the belt member 15 is a strip 29 of inelastic material, as French canvas, for stiffening; and at uniform intervals along the strip 29, before the latter is stitched to the belt, are secured seven male snap fasteners marked 31 to 37. These are selectively usable adjusting fasteners, and they are spaced according to the size of the waist.

A strap 38 of elastic, seven inches in length for a belt of the size above mentioned, is covered with a piece of non-stretchable material at each end; with one such piece, marked 39, on the inner side

of the strap, and with the other such piece, marked 40, on the outer side of the strap.

The piece 39 is longer than the piece 40, as at the former are mounted two female fasteners 41 and 42, while at the latter piece is mounted merely a single such female fastener 43. As will be seen from Fig. 3, the fastener sockets of the fasteners 41 and 42 face outwardly, that is, toward the posts of the fasteners 31 to 37, while the fastener socket of the fastener 43 faces inwardly, that is, toward the post of fastener 27.

The pieces 39 and 40, which not only strengthen the anchorages of the snap fasteners associated therewith and also act to hold the elastic 38 to flatness during stretch and recovery from stretch, are both attached to the strap 38 so as to be locked flatwise there against. This is illustrated in connection with the piece 39, which is stitched all around its four sides to the strap 38.

The elastic strap 38 comprises here the lengthwise resiliently stretchable strap-form belt-auxiliary aforesaid; the same being slidable through the three loops 19, 20 and 21, and constituting, in combination with the various snap fasteners described, an adjustable belt-auxiliary. The fasteners 31 to 37 are spaced according to the waist size designation under which the belt is marketed. The fasteners are three-quarters of an inch apart, so as to allow the belt to be let out two and one-half inches and taken in the same amount.

In attaching the elastic strap 38 to the belt, the strap is sent through all the loops 19, 20 and 21, and the snap fasteners 27 and 43 are coupled. This end of the strap need never be detached. The two snap fasteners 41 and 42 are then coupled with some two adjoining ones of the snap fasteners 31 to 37, depending on the amount of resilient action which is to be exhibited by the elastic strap 38 during and following placement of the belt on the waist of the wearer. When, for instance, the fasteners 41 and 42 are coupled respectively to the fasteners 34 and 33, the belt will measure one and one-half inches less than the actual size of the waist. But the elastic will stretch back three-quarters of an inch, which is sufficient to keep the trousers snug around the waist without dropping; and because of the elastic action the wearer can never feel uncomfortable around the waist line. Coupling of the fasteners 41 and 42 with the fasteners 34 and 33 provides a belt according to the invention especially sized for a thirty-two inch waist.

If desired, the snap fasteners can be reversed; that is, the fasteners on the belt may be female ones, and those on the strap 38 male ones.

When the selected pair of fasteners 31 to 37 have been coupled to the fasteners 41 and 42, following wrapping of the belt around the waist of the wearer, the tongue 16 is inserted first through the loop 20 and then through the loops 19 and 21. The allowed-for stretch of the strap 38 now occurring, the tongue-adjacent end of the belt lies flat against the remainder of the belt, and all other parts of the belt assembly also lie flat. Should the effective length of the belt change, from modified posture or otherwise, all parts of the belt except said tongue-adjacent portion thereof will continue to lie flat; while the ready slidability of the last mentioned portion of the belt through the loops 19, 20 and 21 causes said belt portion automatically to flatten out any temporarily set up bellying therealong. Said portion of the belt thus always

completely covers the entire length of the strap 38.

A feature of the invention illustrated in Figs. 1 and 2 is a downward dipping or curving of the length of the belt 15 which is to lie at the front of the wearer. This curvature, indicated at 46, extending from about hip to hip, is a downward curvature which at its lower point gives a downward dip of about one and one-half inches. Such curvature will keep the belt in balance around the waist of the wearer. To explain:

Trousers of conventional design are cut one and one-half inches higher in the back than in the front. Because of this greater back height, the loops on the trousers' waist are ordinarily sewed on one-quarter to one-half inch lower at the back; but this difference is never enough to keep the belt in balance around the waist.

Consequently, by using floor level measures, it will be found that the top edge around the waist of the trousers will not measure the same. The side measure over the hip-bone will be three-quarters of an inch to one inch higher than that at the front center. The back center will measure one and one-quarter inches to one and one-half inches or over, greater than the front center measure. Because of this a straight belt cannot balance properly around the trousers' waist. It will drop in the back and go up in the front. Therefore, it can never hold up a pair of trousers in the correct position.

The one and one-half inch deep curve 46 across the front of applicant's expansion belt will eliminate these defects, because such curve will automatically raise the back part of the belt the same amount, thus preserving the balance.

The curve 46 can be provided by blocking in with a pressing iron on suitably treated materials such as rayon cotton belting, wool, suede and other pliable materials which can be set to a definite direction of extension by pressing with a hot iron. In the case of leather or plastic belts the curve can be cut in.

Because of the curve 46, the two front loops on the trousers can be eliminated. When the belt is attached to the front of the trousers, as by way of the button hole 23 and a button 24 (Fig. 4) carried by the trousers as already explained, this will be sufficient to support the front of the belt in the correct position. The elimination of the two loops on the front of the trousers would save domestic clothing manufacturers the labor and material cost of making and stitching in place seventy-five million or more loops per year.

The front of the belt may be provided with a sliding buckle for location at the front of the belt when worn. In that case, also present, preferably, is a single loop.

An arrangement pursuant to this way of carrying out the invention is shown in Figs. 5, 6 and 7.

Figs. 5, 6 and 7 are drawn, it will be noted (as was Fig. 3), to avoid attempting to show a curvature, also to be present, corresponding to the curvature 46 of the embodiment first described; and it will also be noted that, as in the case of Fig. 3, Figs. 5, 6 and 7 have been further simplified by omitting any showing of stitchings, except in one case, that is, to show a button hole 47 corresponding to the button hole 23 as and for the purpose already explained.

The buckle is shown at 48, and the single loop at 49.

The parts marked 15', 16', 27', 29', 31' to 37', 38', 39', 40', 41', 42' and 43' correspond respec-

tively to the parts given these reference characters without primes in Figs. 1, 2 and 3.

It will be noted that the strip 29' is placed somewhat differently along the belt 15' than is the strip 29 of Fig. 3. Another difference is that the end 50 of the belt member 15' remote from its tongue 16' is wrapped around the center-bar 51 of the buckle 48 and stitched as at 52 to anchor said end to the buckle.

From the description of the embodiment of Figs. 1-4, the manner of use and the operative features and advantages of the embodiment of Figs. 5, 6 and 7 will be readily understood. The purpose of the button hole 47 is the same as that of the button hole 23. The snap fasteners 27' and 43' are first coupled and may remain coupled at all times.

When, with the elastic strap running through the buckle 48 as shown in Fig. 6, the belt has been placed around the waist of the wearer, the selected pair of snap fasteners 31' to 37' are coupled to the fasteners 41' and 42'. Thereupon, the tongue 16' is also run through the buckle (as shown in Fig. 6), and then through the loop 49, and the tongue is pulled until all slack is drawn up. In this case also, the tongue-adjacent end portion of the belt will be free to slide through its guiding means, here the buckle 48 and the single loop 49, back and forth, in accordance with expansions and contractions of the belt during wear of the same.

While snap fasteners have been shown and particularly described, it will be understood that any practicable and desired equivalents may be employed; as, for instance, hooks and eyes.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A belt comprising a belt member having a tongue end portion and a buckle-carrying end portion, a buckle secured to said buckle-carrying end portion for guiding said tongue end portion, a male snap fastener part secured to said buckle-carrying end portion adjacent said buckle, a row of male snap fastener parts secured to said tongue end portion, and an elastic strip having a female snap fastener part at one of its ends for coaction with said buckle-carrying end portion fastener part, and having a female snap fastener part at the other of its ends for coaction with any one of said tongue end portion fastener parts for adjusting the length of said belt, said belt end portions having overlapping parts and said elastic strip passing between said overlapping parts, said belt being expandable from any of its adjusted positions by stretching of said elastic strip, expansion and contraction of said elastic strip being accompanied by sliding of said tongue end portion in said buckle.

2. A belt comprising a belt member having a tongue end portion, a buckle-carrying end portion, a buckle secured to said buckle-carrying end portion for guiding said tongue end portion, a fastener secured to said buckle-carrying end portion adjacent said buckle, a fastener secured to said tongue end portion, and an elastic strip having at one end a complementary fastener for coaction with the fastener of said buckle-carry-

ing end portion; a complementary fastener on the other end of said elastic strip for coaction with the fastener of said tongue end portion, said belt end portions having overlapping parts and said elastic strip passing between said overlapping parts, said belt being expandable by stretching of said elastic strip, expansion and contraction of said elastic strip being accompanied by sliding of said tongue end portion in said buckle.
